BOX WITH SLIDE COVER AND HANG-UP DEVICE
Lud H. Kimbrough, Jr., Richmond, Va., assignor to Ideal
Fishing Float Company, Inc., Richmond, Va., a cor-
poration of Virginia

Filed Mar. 20, 1961, Ser. No. 97,001
4 Claims. (Cl. 220—18)

The present invention relates generally to a combination slide-type box and hang-up device by means of which goods sold in multiple lots or parts may be conveniently packed and displayed for display, sale and shipment.

It is an object of the present invention to provide an improved combination slide-type box.

Yet another object of the present invention is to provide a box construction with an improved locking arrangement and by means of which the box may be suspended, for example, from a display rack.

Yet another object of the present invention is to provide improved means of merchandising goods having multiple parts or components.

Many other features, advantages and additional objects of the present invention will become manifest to those versed in the art upon making reference to the detailed description which follows and the accompanying sheets of drawings in which a preferred structural embodiment of a combined slide-type box and hang-up device is shown by way of illustrative example.

On the drawings:

FIGURE 1 is an elevational view of a display rack containing a plurality of combined slide-type boxes and hang-up devices in accordance with the principles of the present invention;

FIGURE 2 is a cross-sectional view taken generally on line II—II of FIGURE 1 and illustrating details of construction of the combined slide-type box and hang-up device;

FIGURE 3 is a cross-sectional view of the box of FIGURE 2 taken on line III—III of FIGURE 1; and

FIGURE 4 is an isometric view of the box per se with the slide-type cover partially removed.

As shown on the drawings:

The combined slide-type box and hang-up device of the present invention is shown generally at 10 and as illustrated in FIGURE 1, three units identified at A, B and C are shown suspended from a hook 11 projecting from a display rack 12. The devices are intended to contain plural parts or components of goods having multiple parts or components. One good illustrative example is a box suitable for containing a plurality of swivel-casting lead sinkers wherein the fisherman will desire to have a plurality of such sinkers and perhaps a plurality of such boxes each containing a corresponding plurality of sinkers in different size classifications.

Each combined unit 10 comprises a box 13 having a bottom wall 14, upstanding side walls 16 and 17 and upstanding end walls 18 and 19. In the form of the invention illustrated and as is clearly depicted in FIGURE 4, the box 13 may be somewhat rectangular in configuration so that the side walls 16 and 17 are somewhat longer than the end walls 18 and 19.

Each side wall 16 and 17 has formed at the top margin thereof an outwardly projecting flange 20 and 21, respectively.

The bottom wall 14 has formed on the inside surface thereof a plurality of strengthening ribs 22 which extend across the bottom wall 14 laterally between the side walls 16 and 17 and which are spaced from one another longitudinally along the length of the box.

A cover is shown generally at 23 and has a flat upper surface 24 as well as a flat parallel lower surface 26. At

2

the side margins of the cover along the longitudinal edges and at one end margin there is formed an integral depending flange. The portion of the flange along the end wall is indicated at 27, while the portions extending along the longitudinal edges are identified at 28.

The lowermost edges of the flanges 28 are offset inwardly as at 29, thereby to underlie the flanges 20 and 21 on the box 13. Further, the flanges 28 are notched as at 30 (FIGURE 4), thereby to terminate the flanges 28 short of the opposite end of the cover and facilitating the formation of a throat or opening by means of which the cover may readily be located in position with the bottom surface 26 resting on the upper margins of the walls 16, 17, 18, 19 and on the flat surfaces provided by the flanges 29 and 21 on the box 13. When relative sliding movement of the cover occurs with respect to the box 13, the flanges 20 and 21 will enter the throat or mouth with the flanges 29, 29 underlying the flanges 20, 21 and the cover can then be closed to completely overlie the box until the flange 27 engages against the end wall 19.

Longitudinally inwardly of the flange 27, the cover 23 is formed with a dimpled embossment 31. The spacing dimension between the flange 27 and the embossment 31 is such as to form a seating recess for the end wall 19. Thus, as the cover 23 is advanced on the box 13, a snap-on engagement will occur as the embossment 31 rides over the edges of the end wall 19. Accordingly, the cover 23 may be temporarily locked on the box and whenever it is desired to shift the cover 23, a sufficient axial force is applied between the box and the cover to again ride the embossment 31 over the edge of the end wall 19. The locking device thus provided is also useful in the event the box is separated from the hang-up device, for example, if the fisherman is using the container in his tackle box.

In accordance with the principles of the present invention, the hang-up device comprises a generally rectangular sheet form member provided on one side with a pressure-sensitive adhesive. The width of the hang-up device is either the same as or less than one of the width or length dimensions of the box 13 with which it is associated. In the present illustrative embodiment, the width of the hang-up device is made less than the width of the end walls 18 and 19. Accordingly, one end of the hang-up device, as shown at 40 is arranged inwardly of the end wall 19 and is engaged against the outside surface 41 of the bottom wall 14, with the pressure-sensitive surface adhesively adhered to the bottom wall 14. The hang-up device projects as at 42 beyond the end wall 18 and is reversely folded as at 43 with the pressure-sensitive surface folded back upon itself, thereby to form a suspension tab 44. Thus, the suspension tab 44 is formed of two separate legs, the long leg 46 which underlies the bottom wall 14 and a shorter leg 47 which extends to the end wall 18, whereupon the hang-up device is offset as at 48 and adhesively adhered to the outside surface of the end wall 18, as at 49.

With the cover 23 in place, the hang-up device envelopes the end edge of the cover 23 as at 50 and is offset to form a short longitudinal extending leg 51 which adhesively engages the upper surface of the cover 23 designated at 24, thereby locking the cover 23 in firm assembly with the box.

The suspension tab 44 is provided with an aperture 52 extending through both legs 46 and 47 of the suspension tab 44, thereby facilitating engagement with the hook 11. The box 13 may conveniently comprise a molded plastic material which is transparent, thereby affording visibility of the contents. Further, the outside surface of the hang-up device is suitable for bearing identifying indicia.

Although minor modifications might be suggested by those versed in the art, it should be understood that I wish to embody within the scope of the patent warranted hereon, all such modifications as reasonably and properly come within the scope of my contribution to the art.

I claim as my invention:

1. A combination slide-type box and hang-up device comprising a generally rectangular box having a bottom wall, side and end walls, each of said side walls having an outwardly extending flange on the top margin thereof, a cover member comprising a flat member having a depending end flange formed on one end and a side flange on two longitudinal sides thereof, said side flanges each having an inwardly extending shoulder offset to slidably underlie a corresponding outwardly extending flange on the side walls, said end flange abutting against one of said end walls when said cover member is slidably assembled on said box, a lug formed integrally on the underside of said cover member and being spaced adjacent said end flange to snap over the edge of said one of said end walls, thereby tending to retain said cover in removable assembly with said box, and an elongated generally rectangular sheet form member having a layer of pressure-sensitive adhesive on one side thereof, one end of said sheet form member having said one side engaged against the outside of said bottom wall in adhered assembly therewith and projecting beyond the limits of said bottom wall a predetermined distance, said projecting portion having its said one side folded back upon itself up to one end wall of said box offset from said bottom wall, said projecting portion of said sheet form member being adhesively engaged to said folded back portion to form a suspension tab, said sheet form member being offset from said suspension tab and having portions engaging the outside of said end wall of said box in adhered assembly therewith, the opposite end of said sheet form member being offset from said portions to overlie said cover member in adhered assembly therewith, thereby locking said cover member to said box, and means forming an aperture in said suspension tab for engaging a supporting hook.

2. A combination slide-type box and hang-up device

as defined in claim 1, said box being made of a rigid transparent material for rendering the contents of the box visible.

3. A combination slide-type box and hang-up device comprising a generally rectangular box having a bottom wall, side and end walls, each of said side walls having an outwardly extending flange on the top margin thereof, a cover member comprising a flat sheet having a depending end flange formed on one end and a side flange on two longitudinal sides thereof, said side flanges each having an inwardly extending shoulder offset to slidably underlie a corresponding outwardly extending flange on the side walls, said end flange abutting against one of said end walls when said cover member is slidably assembled on said box, an embossment formed integrally on the underside of said cover member and being spaced adjacent said end flange to snap over the edge of said one of said end walls, thereby tending to retain said cover in removable assembly with said box, and an elongated generally rectangular sheet form member having a layer of pressure-sensitive adhesive on one side thereof, one end of said sheet form member being adhered to said bottom wall and the other end of said sheet form member being adhered to said cover member, the intermediate portions of said sheet form member extending longitudinally to project beyond the other end of said cover member and beyond the other of said end walls, said intermediate portions being engaged with said other of said end walls and being folded back upon itself to form a suspension tab, thereby locking said cover in locked assembly with said box.

4. A combination slide-type box and hang-up device as defined in claim 3, said suspension tab having an aperture formed therein by means of which said box may be suspended from a hook.
